Patented Aug. 23, 1921.

INVENTOR
Charles E. Wehn.

BY Chas. E. Lourand

ATTORNEY

UNITED STATES PATENT OFFICE.

CHARLES E. WEHN, OF ALAMEDA, CALIFORNIA, ASSIGNOR TO LISTO PENCIL COMPANY, OF ALAMEDA, CALIFORNIA, A CORPORATION OF CALIFORNIA.

PENCIL.

1,388,536.

Specification of Letters Patent. Patented Aug. 23, 1921.

Application filed February 9, 1920. Serial No. 357,390.

To all whom it may concern:

Be it known that I, CHARLES E. WEHN, a citizen of the United States, residing at Alameda, in the county of Alameda and State of California, have invented a new and useful Improvement in Pencils, of which the following is a specification.

This invention relates to a pencil and especially to improvements on the structure 10 shown in my former patent, entitled "Pencil," No. 1,302,999, issued May 12, 1919.

One of the objects of the present invention is to provide a pencil which is simple and substantial in construction, cheap to manufacture, easy to manipulate and so arranged that the lead may be readily changed or replaced when worn.

Another object of the invention is to provide means for advancing the lead and particularly a novel form of screw feed mechanism for gradually advancing the lead as the point becomes worn.

Further objects will hereinafter appear.

The invention consists of the parts and the construction, combination and arrangement of parts as hereinafter more fully described and claimed, having reference to the accompanying drawings, in which—

Figure 1 is a side elevation of the pencil.

Fig. 2 is a central vertical longitudinal section through the same.

Fig. 3 is a detailed view of the screw feed mechanism.

Fig. 4 is an end view of Fig. 3.

Fig. 5 is a detailed view of the lead receiver.

Fig. 6 is a cross section on line 6—6, Fig. 2.

Referring to the drawings in detail, A indicates in general a pencil which in this instance consists of a central cylindrical section 2, and a pair of end sections 3 and 4. The central section 2 supports a screw feed mechanism hereinafter to be described, while the tapered end section 3 carries a lead holder 5. The upper end section 4 serves the function of a handle and is provided with an end chamber 6 for the reception of spare leads or the like.

The central section 2 is preferably constructed of metal or other similar substantial material. It is cylindrical in cross section and is provided with a pair of opposed openings 7 to expose a nut 8 mounted therein. This nut 8 is turnably mounted within the

central section 2, but it is secured against end-wise movement at one end by a partition wall 9 of the section 2, and at the opposite end by a shoulder 10 of the section 4. The shoulder 10 is formed on the end section 4 and forms a reduced end thereof by which connection 55 60 is made between the sections 2 and 4.

Carried by the nut 8 and extending therethrough is a screw rod 11. This rod is secured against turning movement and is moved in one direction or the other by means 65 of the nut 8. When advanced in one direction the screw rod 11 enters the chamber 12 formed in the section 3 and when moved in the opposite direction enters the chamber 14 formed in the section 4. The movement of 70 the screw rod 11 in either direction is limited, its movement into chamber 14 being limited by a partition 15, which forms a bottom for the lead receiving chamber 6, and its movement in the opposite direction into 75 chamber 12 is limited by the inner end of the lead holder 5. It is therefore impossible to advance the screw 11 more than a predetermined distance in each direction, and separation of screw 11 with relation to the nut 80 8 is thereby prevented.

To prevent turning movement of the screw rod 11, a flattened surface 16 is formed on one side thereof. This surface 16 extends from end to end of the screw rod 11. By referring 85 to Fig. 2, it will be seen that the screw rod 11 passes through the partition member 9. The opening formed in this member is noncircular as shown at 17 (see Fig. 6) and it therefore serves as a guide for the screw rod 11 90 and a means for securing the same against turning movement. Turning movement transmitted to the nut 8 will therefore only advance or retract the screw 11 longitudinally with respect to section 2. Formed on 95 the forward end of and in axial alinement with the screw rod 11 is a pin 18. This pin 18 passes through the chamber 12 formed in the section 3 and enters a passage 19 formed in the lead receiver 5. A lead 25 placed in the receiver 5 will therefore be advanced when the screw rod 11 is moved in the direction of arrow *a* of Fig. 2 and it is therefore possible to readily advance the lead 25 as it becomes worn. The lead receiver 5 is preferably constructed of metal. Its inner end is exteriorly threaded as at 20 to engage threads formed on the interior of and near the for 100 105

ward end of the chamber 12 and its outer end is tapered and split as at 21 to frictionally engage the lead 25. The receiver 5 is also shouldered as at 22 to permit it to be readily 5 grasped and turned when it is inserted into or removed from section 3.

From the foregoing description it can be seen that a pencil of simple and substantial construction has been provided, said pencil 10 consisting of a central section and a pair of end sections, the central section serving as a support or container for the screw feed mechanism, the lower end section, the function of a lead receiver, and the upper section the 15 function of a handle and a spare lead receiver. The nut carried by the central section may readily be turned and engaged by the fingers to turn it in one direction or the other, due to the openings 7 formed therein 20 and it is therefore possible to advance a lead, when worn, by merely transmitting a turning movement to the nut. The end sections 3 and 4 are preferably cemented or otherwise secured with relation to the central section 2 25 and when so secured form an integral structure which cannot be separated. This is of importance as it prevents tampering with the interior mechanism. The only part that can be removed is the lead receiver 5 and a removable cap 24 by which the outer open end 30 of the spare lead receiving chamber 6 formed in the upper end of section 4 is closed. In fact it is not necessary to remove the lead receiver 5 as the rod 18, formed on the end of 35 the screw 16, is sufficiently long to project through receiver 5. This insures a complete discharge of the worn lead and it similarly permits a new lead to be inserted from the outer end 21 of the lead receiver 5 when the 40 screw rod 11 is completely retracted within sections 2 and 4.

Having thus described my invention, what I claim and desire to secure by Letters Patent is—

- 45 1. A pencil comprising a hollow cylindrical shell, said shell being pointed at one end and having a central lead receiving passage formed therein, a screw rod within the shell in alinement with the lead receiving passage, 50 a flattened surface formed on one side of the screw rod and extending from end to end thereof, a nut turnably mounted on the screw rod, a partition member within the shell formed with an opening through which the 55 screw rod extends, said opening having a periphery complementary to that of the screw rod whereby said screw rod is free to move longitudinally but held against turning movement.
- 60 2. In a device of the character described the combination with a feeding nut, of a screw rod extending therethrough, said screw rod having a flattened surface formed on one side and extending from end to end,

a guide member associated therewith comprising a member disposed transversely to the screw and having an opening complementary to that of the screw whereby said screw is permitted to move longitudinally but held against turning movement. 65 70

3. A pencil comprising a hollow cylindrical shell, said shell being pointed at one end and having a central lead receiving passage formed therein, a screw rod within the shell in alinement with the lead, a pin on the 75 forward end of the screw rod engageable with the lead and adapted to enter the lead receiving passage, a nut turnably mounted on the screw rod, a key-way on the screw rod, and a member in the shell engaging 80 the key-way to secure the screw rod and the pin carried thereby against turning movement.

4. A pencil of the character described, comprising two tubular end sections and an 85 intermediate tubular section to which said end sections are secured, and one end section being tapered and having a lead passage formed therein, an interiorly threaded nut carried by the intermediate section and turnable 90 therein, a threaded rod adapted to be advanced or retracted by said screw, said threaded rod having a flat surface extending from end to end thereof, and a partition wall adjacent the screw having an opening 95 formed therein through which the threaded rod may pass, said opening having a periphery formed with a flat surface complementary to that of the threaded rod whereby the rod is permitted to move longitudinally but held 100 against turning movement.

5. A pencil of the character described comprising two tubular end sections and an intermediate tubular section, one end section being tapered and having a lead receiving passageway formed therein, an interiorly threaded nut carried in the intermediate section and turnable therein, means for holding said rod against longitudinal movement, a threaded rod adapted to be advanced 110 or retracted by said screw, said rod having a flat surface extending from end to end thereof, a partition wall adjacent the screw having an opening through which the threaded rod may pass, said opening having 115 a periphery formed with a flat surface complementary to that of the rod whereby said rod is permitted to move longitudinally but held against turning movement.

6. A pencil comprising a hollow cylindrical shell, said shell being pointed at one end and having a central lead receiving passage formed therein, a screw rod within the shell in alinement with the lead receiving passage, a flattened surface formed on one side of the 125 screw rod and extending from end to end thereof, a nut turnably mounted on the screw rod, a partition member within the shell

formed with an opening through which the screw rod extends, said opening having a periphery adapted to coöperate with the flat surface formed on the screw rod to permit 5 said screw rod to move longitudinally but hold the same against turning movement.

7. In a pencil of the character described a pair of tubular sections, a comparatively short intermediate tubular section interposed 10 between the first named tubular sections and connecting the same, a nut within the intermediate section supported thereby and turnable therein, a screw rod extending through the nut, and means in the intermediate tubular section for guiding the rod and 15 securing it against turning movement.

8. In a pencil of the character described a pair of tubular sections, a comparatively short intermediate tubular section interposed 20 between the first named tubular sections and connecting the same, a nut within the intermediate section supported thereby and turnable therein, a screw rod extending through the nut, means in the intermediate tubular 25 section for guiding the rod and securing it against turning movement, and a pair of opposed openings formed in the intermediate

tubular section to permit the nut to be grasped and turned.

9. A pencil of the character described 30 comprising a pair of tubular shell sections of approximate equal length, a comparatively short intermediate tubular section connecting the same, a nut within the intermediate section supported thereby and turnable 35 therein, a screw rod extending through the nut and entering the tubular shell sections, a flattened portion on the rod extending from end to end thereof, an end plate secured in the intermediate tubular section, an 40 opening formed in said plate forming a guide for the screw rod and securing the screw rod against turning movement, a plunger on the forward end of the screw rod and a lead receiving member carried by one 45 of the tubular shell sections into which the plunger rod extends.

In testimony whereof I have hereunto set my hand in the presence of two subscribing witnesses.
